AUXILIARY VENTURI VACUUM ADAPTER
FOR VACUUM CONTROLLED SPARK AD-
VANCE

Garth L. Young and William Ostling, Los Angeles, Calif., assignors to California Machinery and Supply Co. Ltd., Los Angeles, Calif., a corporation of Delaware

Application August 31, 1946, Serial No. 694,266

10 Claims. (Cl. 123—117)

1

This invention relates to a spark control mechanism for spark ignition internal combustion motors.

This invention is an improvement upon the spark control mechanism and method of the Vanderpoel et al. Patent No. 2,249,446, and other similar spark control devices and methods.

In such methods the advance of the spark is controlled to respond to the joint action of the vacuum at the throttle and at the venturi.

The fuel induction system carries an orifice positioned at the throttle so that it is on the carburetor side of the throttle in idling position and on the manifold side of the throttle when the throttle is in part open position. Another orifice is placed at the Venturi throat of the carburetor; a tube connected to both orifices is in turn connected to a chamber in the distributor in which a diaphragm is placed; and the diaphragm moves a rod which causes an adjustment of the spark advance in the distributor.

In this fashion the advance responds to the vacuum as generated at the throttle orifice modified by the vacuum generated at the Venturi orifice.

The vacuum generated at the Venturi throat for any given air flow resulting from the pumping effect of the engine at any given R. P. M. is limited by the discharge coefficient of the venturi. This discharge coefficient for carburetors substantially is less than can be obtained from a well designed venturi, because of the effect of the fuel nozzles. Fuel injected through the nozzles, chokes and throttles introduces fluid friction in the Venturi throat and on both sides of the Venturi throat. Thus, even for the most efficient of commercial types of carburetors the discharge coefficient is rarely greater than about .8.

The improvement of this invention consists broadly in introducing a second venturi ahead of the carburetor venturi and ahead of the fuel injection point and placing the Venturi orifice at this auxiliary venturi instead of at the carburetor venturi. Compared with a discharge coefficient of about .8 for a conventional carburetor venturi, we can, by employing a well designed venturi free of such fluid friction creating devices, obtain a discharge coefficient substantially greater than .8 and as much as .95 or greater. By employing an auxiliary venturi and placing the Venturi orifice at such venturi instead of the carburetor venturi, we may obtain for the same air flow a materially lower pressure at the Venturi orifice than is obtainable for the

2

same air flow when the Venturi orifice is located in the carburetor venturi.

The result of this modification is that the influence of the Venturi orifice upon the spark setting is magnified above that which the Venturi orifice has in the prior art devices. This is particularly true under the conditions of road load or full load where the prior art devices operate to cause too great a retard at road load and at full load operations. With the improvement of our invention the spark advance at full load and at road load conditions more closely approximates engine requirements at these load conditions for optimum horsepower output.

15 In such systems where, as is usual, a choke valve is placed ahead of the carburetor venturi, when the choke is closed, as, for example, during starting or idling, the pressure in the Venturi orifice and at the throttle orifice may fall so low 20 as to cause an undesirable advance of the spark. In order to avoid this possibility, the prior art has employed various expedients for insuring that the spark would be held retarded during idling or cranking when the choke was closed. In our 25 device, due to the fact that on closing of the choke the Venturi orifice is on the atmospheric pressure side of the choke, a high pressure is exerted at the Venturi orifice, and even though the pressure at the throttle orifice falls to a low 30 level, the Venturi orifice bleeds into the diaphragm chamber to insure that the spark is retarded.

This invention and its objects will be further described in connection with the drawings, in which:

Fig. 1 is a view in part section of the carburetor and spark advance mechanism of our invention; and

Fig. 2 shows a detail of one modification of the system of Fig. 1.

The carburetor is connected at flange 2 to the engine manifold of a conventional spark ignition internal combustion motor. The carburetor contains the conventional air induction tube 1, the 45 throttle 3, venturi 4, carrying a fuel injection nozzle 5 and a choke 6, as conventional.

Mounted on shoulder 7 is the auxiliary venturi 8 of our invention. The Venturi section carries an external shoulder 9 on which is mounted 50 an air cleaner 10 and the assembly held in place by means of clamping ring 11 and ear 11a. This venturi is preferably positioned so that its discharge coefficient is not influenced by the frictional effects of the carburetor or choke or the air cleaner. It is desired to make its constants,

such as throat diameter and streamlining, such as to give the maximum vacuum at the attained rate of air flow. For this reason it is placed sufficiently away from the air cleaner and ahead of the choke to give maximum efficiency.

Positioned at the throttle 3 is an orifice 13 and bore 14 drilled in the boss 12 so that the orifice 13 is on the carburetor side of the throttle 3 when the throttle is in cranking or idling position and on the manifold side when the throttle is in road load, i. e., part open position.

In the bore 14 fitting is received. The fitting 15 has a conduit 16 which is connected to tube 17 by a fitting 18.

A second orifice 19 is positioned at the throat or veni contracti of the venturi 8. In the conical bore 20 is screwed a fitting 21 having a cross bore 22 coaxial with 20 and a cross bore 23 to which the tube 17 is connected by means of fitting 24. The bore 22 is connected to tube 26 by means of fitting 25.

The spark setting and distributors device 27 is conventional except for the following modification. It is provided with a cam 28 of usual design operating on shaft 29. Around the shaft is rotatably mounted a breaker plate 30 carrying a conventional breaker 30a. This breaker plate, in order to adapt it to our invention, is formed with an upstanding pin 30b and a bore 31 through which protrudes a pin 32 positioned on an adjustable plate 33 mounted in the casing of the distributor 27 beneath the breaker plate 30. A spring 34 is mounted on pins 30b and 32. The rod 35 is connected to the plate 30 by hinge 36 and to the diaphragm 37 positioned in the airtight chamber 39 formed by cover 38. The tube 26 is connected to the chamber 39 by a fitting 40.

While we have described one form of device, other forms may be readily adapted to this use, as will be understood by those skilled in the art.

Fig. 2 shows a modified fitting to take the place of fitting 15 of Fig. 1. The tube 42 is screwed into the bore 14 and into the fitting 41 carrying a valve chamber 43 in which is positioned the spring 45 and ball check valve 44 which seats against the fitting 46 to close the conduit 47.

The operation of the vacuum controlled spark advance, as shown in Fig. 1, is as follows:

Engine at rest: When the engine is at rest, atmospheric pressure exists above and below the diaphragm 37 and the spring 34 moves the breaker plate to full retard position.

Cranking: While cranking the throttle is at idling position, as shown in Fig. 1; the flow of air through the venturi 8 past the orifice 19 and also past the orifice 13 is low; and a relatively high pressure exists in the conduits 20, 14, and 26 and chamber 39. The degree of vacuum thus generated in chamber 39 is insufficient to move the diaphragm with a force sufficient to overcome the tension in spring 34 and the spark remains in full retard position. The closing of the choke valve 6 will cause the pressure at the Venturi orifice 19 to rise, thus insuring that the spark will remain retarded during cranking even though the choke is closed or partly closed.

Idling: As the motor speeds up to idling speed, the throttle remains in cranking position, as shown in Fig. 1. There is an increase in the rate of flow of air past the orifices 19 and 13 but insufficient to create a vacuum in line 26 and chamber 39 and sufficient to overcome the tension in spring 34, and the spark remains in full retard position. The part closing of the choke

in this operation acts as in the case of cranking, thus insuring the retarding of the spark during idling even though the choke is closed or partly closed.

Road load conditions.—As the throttle is opened wider to part throttle position, the throttle orifice 13 is placed on the manifold side of the throttle. The air flow increases, resulting in a decrease in the pressure on the throat of the venturi. The pressure at the throttle orifice 13 drops substantially to the intake manifold vacuum. The vacuum in lines 17 and 26 is not, however, that of the manifold vacuum, since the pressure in the Venturi throat 8 is greater than the manifold vacuum. There is therefore an air bleed via 19, 20, and 17, causing the pressure in the line 26 to reach some pressure intermediate that of the pressure at 19 and 13. The reduction in pressure in 39 causes the diaphragm 37 to move the rod 35 and rotate the breaker plate 30 against the spring 34 to adjust the angular relation of the breaker plate and cam and advance the spark.

It will be observed that the advance effected is less than would be obtained where the tube 26 is connected to 13 only (i. e., in the absence of orifice 19) by the bleeding effect of the orifice 19. This prevents the over advance of the spark at road load conditions.

Comparing the effect of positioning the orifice 19 at 8 instead of at the throat 4, as in the prior art, it will be seen that since the discharge coefficient of venturi 4 is usually about 85 to 90% of the attainable discharge coefficient of 8, the pressure in the throat of 4 is considerably greater for like air speeds than that attainable at the throat of 8. Therefore, the vacuum attained in tube 26 is greater than would be attained for the same throttle setting where the orifice is at the throat of 4. This means that the spark advance will be greater for the same engine speeds.

Full load conditions.—As the throttle is opened wider to full throttle position the pressure in the intake manifold rises and the pressure at the orifice 13 is then greater than at the throat of the venturi 8. The direction of the air bleed is therefore from 13 through 17 into 22, to modify the vacuum created by the air flow through the venturi 8. The pressure in the tube 26 is higher than at part throttle operation and the distributor moves to part retard.

It will be observed that here also the increased vacuum in the throat of 8 as compared with that attainable in 4 causes the pressure in 26 to be lower than it would have been where the orifice 19 is at 4 and the spark is prevented from being over retarded.

The operation of the device as modified in Fig. 2 is as follows:

Engine at rest.—The conditions are similar to those described above. The check valve is seated as in Fig. 2.

Cranking.—There is insufficient difference in pressure to unseat the ball 44. The operation is as described above in connection with Fig. 2.

Idling.—The pressure difference is sufficient to unseat the valve, and the operation is similar to that described above in connection with Fig. 2.

Road load.—The pressure in 17 modified by the higher pressure at 19 is higher than at 13, the ball remains unseated, and the operation is as described above in connection with Fig. 2.

Full load condition.—Since in this condition the pressure at 13 is greater than at 19, the ball

seats and the tube 26 is subjected to the vacuum at 19. Since this is now unmodified by the pressure at 13, the vacuum in 26 is higher for the same position of the throttle and a greater degree of spark advance is obtained than that obtained for Fig. 1.

While we have described a particular embodiment of our invention for the purpose of illustration, it should be understood that various modifications and adaptations thereof may be made within the spirit of the invention as set forth in the appended claims.

We claim:

1. In combination, an ignition timer and carburetor for an internal combustion motor, comprising an air intake passageway, a venturi in said passageway, an air discharge conduit from said venturi, a carburetor, a carburetor venturi, an associated fuel injection nozzle, an air inlet to said carburetor venturi connected to said first-mentioned venturi, a fuel and air discharge conduit from said carburetor, a throttle in said air and fuel discharge conduit, means for attaching said air and fuel discharge conduit to the manifold of an internal combustion engine, an orifice in the throat of said first-mentioned venturi and an orifice at said throttle, said orifice at said throttle being positioned so that it is on the carburetor side of the throttle when the throttle is in idling position and on the manifold side of said throttle when the throttle is in part open position, a by-pass conduit connected to both of said orifices, an ignition timer, a pressure responsive device for advancing and retarding the spark advance setting of said ignition timer, said last-named conduit being also connected to said pressure responsive device.

2. In combination, an ignition timer and carburetor for an internal combustion motor, comprising an air intake passageway, a venturi in said passageway, an air discharge conduit from said venturi, a carburetor, a carburetor venturi, an associated fuel injection nozzle, an air inlet to said carburetor venturi connected to said first-mentioned venturi, a fuel and air discharge conduit from said carburetor, a throttle in said air and fuel discharge conduit, means for attaching said air and fuel discharge conduit to the manifold of an internal combustion engine, an orifice in the throat of said first-mentioned venturi and an orifice at said throttle, said orifice at said throttle being positioned so that it is on the carburetor side of the throttle when the throttle is in idling position and on the manifold side of said throttle when the throttle is in part open position, a by-pass conduit connected to both of said orifices, an ignition timer comprising a cam, a breaker arm operated by said cam, a cam shaft upon which said cam is mounted, means for adjusting the advance of said spark by adjusting the angular relationship of said cam and arm comprising an arm for moving said breaker arm relative to said cam, a diaphragm connected to said arm, a chamber in which said diaphragm is mounted, said by-pass conduit being connected to said chamber.

3. In the device of claim 1, a check valve in said by-pass conduit between the throttle orifice and said Venturi orifice and the point of connection of said by-pass conduit and said pressure responsive device, said check valve being closed when the pressure at the throttle orifice is greater than at the Venturi orifice.

4. In the device of claim 2, a check valve in said by-pass conduit between the throttle orifice and

said Venturi orifice and the point of connection of said by-pass conduit and said chamber, said check valve being closed when the pressure at the throttle orifice is greater than at the Venturi orifice.

5. A carburetor for an internal combustion engine, comprising an air intake passageway, a venturi in said passageway, an air discharge conduit from said venturi, a second venturi in said passageway, a fuel injection nozzle associated with said second venturi, an air inlet to said passageway connecting said first mentioned venturi and said second mentioned venturi, a fuel and air discharge conduit from said second venturi, a throttle in said air and fuel discharge conduit, means for attaching said air and fuel discharge conduit to the manifold of an internal combustion engine, an orifice in the throat of said first-mentioned venturi, an orifice in the wall 15 of said conduit at said throttle, said orifice being positioned so that it is on the fuel injection side of said throttle when said throttle is in idling position and on the manifold side of said throttle when said throttle is in part open position, a by-pass conduit connected to both of said orifices, and means for connecting said by-pass conduit to an ignition timer.

6. In the device of claim 5, a check valve in said by-pass conduit between the throttle orifice and 30 said Venturi orifice and the point of connection of said by-pass conduit to said ignition timer.

7. A carburetor for an internal combustion engine, comprising an air passageway, a fuel injection nozzle in said passageway, an air fuel 35 outlet from said passageway, an air inlet to said passageway, a throttle in said passageway on the discharge side of said passageway, a choke valve positioned in said passageway near the air inlet side of said passageway, said fuel injection nozzle being positioned between said choke and said 40 throttle, a venturi in said passageway, said choke being positioned in said passageway between said venturi and said fuel injection nozzle, an orifice at the throat of said venturi, an orifice at said 45 throttle, said orifice at said throttle being positioned so that it is on the fuel injection side of the throttle when the throttle is in idling position and on the manifold side of said throttle when the throttle is in part open position, a by-pass 50 conduit connecting both of said orifices, and means for connecting said by-pass conduit to a pressure-responsive ignition timer.

8. In the device of claim 7, a check valve in said by-pass conduit between said throttle orifice 55 and said Venturi orifice and the point of connection of said by-pass conduit to said pressure-responsive ignition timer.

9. A combination of an ignition timer and a carburetor for an internal combustion engine, 60 comprising an air intake passageway, a venturi in said passageway, an air discharge conduit from said venturi, a fuel injection nozzle in said carburetor, a fuel and air discharge conduit from said carburetor, a throttle in said air and fuel discharge conduit, a choke valve between said venturi and said fuel injection nozzle, means for attaching said air and fuel discharge conduit to the manifold of an internal combustion engine, an orifice in the throat of said venturi, an orifice 65 at said throttle, said orifice at said throttle being positioned so that it is on the carburetor side of the throttle when the throttle is in idling position and on the manifold side of said throttle when said throttle is in part open position, a by-pass conduit connected to both of said orifices, 70 and means for connecting said by-pass conduit to a pressure-responsive ignition timer.
